merding, Pa., a corporation of Pennsylvania

Application December 4, 1947, Serial No. 789,671

6 Claims. (Cl. 74—505)

1

This invention relates to winding mechanism and more particularly to hand operated type for applying brakes on a railway vehicle, or the like.

One of the objects of the invention is the provision of a new and improved winding mechanism that, during initial rotation of an operating handle in one direction, will rapidly take up slack in a brake rigging or the like, and that on final rotation of the handle in the opposite direction will have increased leverage, as for applying the brakes.

Another object of the invention is the provision of a new and improved mechanism that is self-locking in operation and therefore particularly adapted for use in applying hand brakes on a vehicle.

Another object of the invention is the provision of an improved winding mechanism which comprises means for controlling the rate of release thereof.

Other objects and advantages of the invention will become apparent from the following more detailed description thereof, taken in connection with the accompanying drawings, in which,

Fig. 1 is a diagrammatic view, partly in outline and partly in section, of a winding mechanism embodying the invention; and

Fig. 2 is a fragmentary view taken in the direction of arrow 2 in Fig. 1.

Description

Referring to Fig. 1, reference numeral 5 designates a casing, which may be mounted at any convenient location on a railway car (not shown) such as on the end thereof, containing gear mechanism 6 adapted to be operated by an operating handle in the form of a hand wheel 7 for turning a shaft 8 connected to a drum 9 on which is wound a cable 10 adapted to be operatively connected to a device to be actuated, such as the brake rigging (not shown) of a railway vehicle.

The hand wheel 7 is secured to one end of a shaft 11 adapted to turn within a bore 12 extending through the casing 5. A gear 13, within the casing, is secured to the opposite end of shaft 11 for operative engagement with a larger gear 14 which is suitably arranged for rotation about a fixed axis relative to the casing, by some such arrangement as is shown in the drawing in which a central hub 15 of said gear is rotatably mounted on the outer surface of a sleeve boss 16 attached to and projecting inwardly from the casing. The gears 13 and 14 are preferably in the form of bevel gears with their axes at right angles to each other for favorable disposition of the hand

wheel 7, but said gears might be in the form of spur gears with their axes parallel to each other by relocation of said hand wheel relative to the casing.

A frame 17 is secured to the gear 14 for rotation therewith. The frame 17 may comprise two spaced apart arms 18 and 19 rigidly secured at their one end to the gear 14, each disposed equidistant from the projected axis of said gear and parallel thereto, and a member 20 secured to and extending between the opposite ends of said arms and disposed transversely of said projected axis. The frame 17 is thereby adapted to turn about the same axis as the gear 14, and may be rotatably supported at its end away from said gear by a sleeve shaft 21 secured to member 20 and mounted in a bore 22 extending through one end of the casing 5 in alignment with sleeve shaft 16 at the opposite end of said casing.

Two oppositely arranged dual element bevel gears 23 and 24 of equal size are disposed within the frame 17. The dual element bevel gear 23 is secured for rotation with a central shaft 25 journaled to the arm 18. The dual element bevel gear 24 is secured for rotation with a central shaft 26 journaled to the arm 19. Both shafts 25 and 26 are in alignment one with the other, and their axes project in a direction at right angles to the direction of the axis of gear 14.

Each of the dual element bevel gears 23 and 24 comprises two attached bevel gear elements 27 and 28, element 28 being of larger diameter than element 27 and disposed adjacent to the respective arm of frame 17. The gear elements 27 are arranged for simultaneous engagement at their corresponding opposite sides with two spaced apart bevel gears 29 and 30 of equal diameters extending between said elements. The gear 29 is secured to one end of a hollow shaft 31 which is journaled in the sleeve boss 16 attached to the casing and projects therethrough. The gear 30 is secured to one end of a shaft 32 which is journaled in and extends through the hollow shaft 31. To the outer end of hollow shaft 31 is attached a ratchet wheel 33 which is provided with the usual teeth for normal engagement by a pawl 34 for preventing counterclockwise rotation of the shaft 31 and gear 29, as viewed in the direction of the arrow 2 in Fig. 1. To the outer end of shaft 32 is attached a ratchet wheel 35 substantially similar to wheel 33, having teeth for normal engagement by a pawl 36 for preventing rotation of said shaft and hence gear 30 in the opposite direction, or clockwise, as viewed in the same manner as above mentioned. For biasing the re-

spective pawls 34 and 36 in the direction of the respective ratchet wheels 33 and 35 a tension spring 37 may be connected at its opposite ends to each of said pawls.

The pawls 34 and 36 are each pivotally secured by suitable means to respective bosses 38, 39 or the like, projecting from the casing 5. Levers 40 and 41 are provided on pawls 34 and 36, respectively, for engagement by an unlocking cam 42. The cam 42 may be circular in transverse cross-section and is secured for eccentric turning movement about an off-center pin 43 fixed to the casing 5, a release handle 44 being provided for effecting said movement. The handle 44 is adapted to be moved to any one of three positions, a "Lock" position, in which it is shown in the drawing, a "Slow release" position, and a "Quick release" position. In "Lock" position of handle 44, the cam 42 is so positioned as to be out of effective displacing engagement with both of the levers 40 and 41, so that under action of spring 37, the pawls 34 and 36 are in normal locking engagement with the teeth of the respective ratchet wheels 33 and 35. In "Slow release" position, the cam 42 is in effective displacing engagement with lever 40 whereby pawl 34 is held out of locking engagement with ratchet wheel 33. In "Quick release" position, the cam 42 is in effective displacing engagement with both the lever 40 and the lever 41 whereby both pawls 34 and 36 are held out of locking engagement with the respective ratchet wheels 33 and 35. The significance of these positions of the cam 42 and handle 44, as above described, will hereinafter become obvious.

A relatively large bevel gear 45 is disposed within the frame 17 in alignment with the axis of gear 14 and in operable engagement with both of the bevel gear elements 28, for turning the shaft 8 and drum 9 secured thereto. Shaft 8 is journaled in the sleeve shaft 21 and extends outwardly through the casing.

The cable 19 is wound on the drum 9 and may be operatively connected to the usual brake rigging (not shown) for setting brakes on a railway vehicle or the like employing the mechanism.

Operation

For the purpose of illustration, assume that the winding mechanism above described is applied to a railway vehicle for applying the brakes thereon by hand. Further assume that the brakes are released; that the cable 19 is operatively connected thereto and is so wound on drum 9 that, as viewed in the direction of arrow 2, rotation of the drum counterclockwise will cause winding of said cable on said drum to apply the brakes, while rotation in the opposite direction will cause unwinding for releasing the brakes; and that initially there is considerable slack in the cable 19; and further that the release handle 44 is in "Lock" position with both of the pawls 34 and 36 in locking engagement with the respective ratchet wheels 33 and 35, in manner as previously described.

If it is desired to apply the vehicle brakes by operation of the hand-operated winding mechanism, as viewed in the direction of an arrow 50 the hand wheel 7 will first be rotated in a clockwise direction, turning the connected gear 13 in the same direction.

As viewed in the direction of arrow 2, the above turning of gear 13 will turn the larger gear 14 in a counterclockwise direction relative to the casing 5. If it is now assumed that the hand wheel 7

wheel is turned a sufficient number of times to cause the gear 14 to make a complete revolution, the frame 17 will also make a complete revolution relative to the casing 5 and in the same direction. 5 As the frame 17 makes one revolution counterclockwise, the dual element bevel gears 23 and 24 will be carried, with their respective shafts 25 and 26, also a full revolution with the frame 17. In so doing, the bevel gear elements 27 will 10 roll on the gear 29 attached to shaft 31, which is secured against counterclockwise rotation by engagement of the pawl 34 with the ratchet wheel 33, the elements 27 turning about their own axes on the respective shafts 25 and 26, and 15 thereby causing the bevel gear 30, shaft 32 and ratchet wheel 35 to turn in a counterclockwise direction.

The number of revolutions that each of the 20 elements 27 will make about their respective axes during their counterclockwise revolution with the frame 17 and gear 14, will equal the ratio of the number of teeth on gear 29 to the number of teeth on said elements. For example, if the gear elements 27 have fifteen teeth, and 25 the gear 29 has thirty teeth, each of said elements will make about its respective axis two revolutions for each revolution of gear 14. The gear elements 28, attached to elements 27, will 30 make the same number of revolutions about the same respective axes, or for example two revolutions, and obviously in the same direction, which direction is such as will cause the gear 45, shaft 8 and drum 9 to turn counterclockwise, as viewed in the direction of arrow 2. The number of 35 revolutions that the gear 45 will make in a counterclockwise direction relative to the casing 5 for one revolution of the gear 14 and frame 17 in the same direction will equal the ratio of the number of teeth on the elements 28 to the number 40 of teeth on gear 45 multiplied by the number of turns that said elements 28 make on their own axes during that revolution of frame 17, plus one revolution of the elements 28 with the gear 14 and frame 17, since, if said elements were not 45 to turn at all on their own axes, as they were carried a complete revolution with said frame, they would cause the gear 45 to complete one revolution relative to the casing.

To continue the above example, if the gear elements 28 have thirty teeth, and the gear 45 forty teeth, during one revolution of the gear 14 and frame 17 as above described, the gear elements 28 make two revolutions about their own axes, and the gear 45 will make two and one-half 55 revolutions in a counterclockwise direction relative to the casing, as viewed in the direction of the arrow 2. The drum 9 connected to gear 45 will thus be caused to rotate in a counterclockwise direction, winding the cable 19 thereon and 60 taking up slack in said cable or brake rigging.

When the resistance to rotation of the drum 9 increases substantially, as when the brake shoes engage the wheels, and as indicated to an operator by increased resistance to rotation of the hand wheel 7, the operator may turn the hand wheel in the opposite direction, or in a counterclockwise direction as viewed in the direction of the arrow 50, for applying the brakes on the vehicle.

Rotation of the hand wheel 7 in a counterclockwise direction will rotate the gear 13 in the same direction, and as viewed in the direction of the arrow 2, will rotate the larger gear 14 in a clockwise direction. Now to simplify the following description, assume that the hand wheel 7

5

is rotated, as above, a sufficient number of turns as will cause the gear 14 to make one complete revolution in the clockwise direction, carrying the frame 17 with it in the same direction.

As before, rotation of the frame 17 will carry the dual element bevel gears 23 and 24 and their shafts 25 and 26 with it, but this time in the opposite direction, or clockwise one revolution. During such revolution of the frame 17, the gear elements 27 will roll on the gear 30, which is secured against clockwise rotation by engagement of pawl 36 with ratchet wheel 35, and thereby be caused to rotate about their respective axes. The gear 29 will not prevent such rotation, it being free to turn in a clockwise direction causing the pawl 34 to jump the teeth of ratchet wheel 33. During this revolution of the frame 17 in a clockwise direction, the gear elements 27, and hence attached elements 28, will rotate in the same direction about their respective axes as during the previously described revolution of said frame in the counterclockwise direction, due to the fact that in the second instance elements 27 roll on gear 30 which is fixed, whereas in the first instance said elements rolled on the gear 29 which was then fixed. Further, since the gears 29 and 30 are the same size and have the same number of teeth, and the gear elements 27 in rolling on one will make the same number of revolutions about their respective axes as in rolling on the other, and in the same direction as was pointed out, which direction is such as will cause the attached elements 28 to rotate the gear 45 in a counterclockwise direction as before. In making a revolution in circuit with the frame 17 in the clockwise direction, however, the dual gear elements 23 and 24 carried by said frame and in engagement with the gear 45 will tend to carry said gear one revolution in the same clockwise direction, so that the net revolutions that the gear 45 will make in a counterclockwise direction, under the above circumstances, will equal the number of turns it tends to make in a counterclockwise direction as caused by rotation of said elements about their respective axes, less one revolution in circuit of the elements 28 with the frame 17 in the opposite or clockwise direction.

For example, if gear elements 27 and 28, and gears 30 and 45, have the number of teeth previously assumed, then in rotating gear 14 one revolution in a clockwise direction, as effected by turning the hand wheel counterclockwise, the dual element gears 23 and 24 will turn two revolutions on their respective axes, as before, and will tend to cause gear 45 to turn one and one-half revolutions in a counterclockwise direction, also as before, but in this instance, less one revolution of circuit in a clockwise direction, or a net of one-half revolution in a counterclockwise direction, causing the drum 9 to so turn also, further winding the cable 10 thereon at a greater mechanical advantage for applying the brakes on the railway vehicle.

It will thus be seen that by turning the hand wheel 7 first in a clockwise direction, the operator may cause the slack in the cable 10 and brake rigging to be taken in rapidly, bringing the brake shoes into contact with the wheels, and then by turning said hand wheel in an opposite or counterclockwise direction, he may cause a pull to be exerted on the cable for applying the brakes at a greater leverage. The relationship of speed ratio and force ratio between turns of hand wheel 7 and effort exerted thereon, to turns of drum 9 and pull on cable 10, all other factors

6

such as size of gears 13, 14 and of drum 9 remaining constant, will depend upon the relative sizes and number of teeth on gear elements 27, 28, and gears 29, 30 and 45, as will be obvious.

After the brakes have been set, they are held in this position by automatic locking action of the pawls 34 and 36. In order for the brakes to release, the cable 10 would need to unwind from the drum 9 and thereby cause said drum and gear 45 to turn in a clockwise direction. In order for the gear 45 to turn in a clockwise direction, either the dual element gears 23 and 24 must be free to turn on their respective axes so as to roll on gears 29 and 30 and thereby permit frame 17 to turn in either a clockwise or a counterclockwise direction, or said gears must be free to turn on their respective axes while the frame 17 remains stationary. To permit the frame 17 to turn clockwise, the gear elements 27 of gears 23 and 24 would need to be free to roll on gear 29 while turning gear 30 in a counterclockwise direction which is prevented by engagement of pawl 36 with ratchet wheel 35 attached to gear 30. To permit the frame 17 to turn counterclockwise, the elements 27 would need to be free to roll on gear 30 while turning the gear 29 counterclockwise, which is prevented by engagement of pawl 34 with ratchet wheel 33 attached to gear 29. To permit gears 23 and 24 to rotate on their respective axes without causing movement of frame 17, the elements 27 thereof need be free to permit gear 30 to rotate in a clockwise direction while gear 29 is permitted to rotate in a counterclockwise direction, which neither is free to do, as will be obvious from the previous description. The gear 45, drum 9 and hence cable 10 are therefore locked in position during application of the brakes, thus preventing an unintended release thereof.

When it is desired to release the brakes on the car at a controlled rate or to a chosen degree after an application, either pawl 34 or 36 may be disengaged from the respective ratchet wheel; but I prefer to disengage the pawl 34 for this purpose, and to disengage pawl 34, the handle 44 may be moved to "Slow release" position for causing said pawl to disengage from the ratchet wheel 33 to thereby allow the gear 29 freedom of movement in either direction.

The hand wheel 7 may then be rotated in a counterclockwise direction to control the release of the brakes as desired. For the sake of simplifying the description of "Slow release" operation, assume that hand wheel 7 is rotated a sufficient number of turns in a clockwise direction to cause the gear 14 to make one revolution in a counterclockwise direction, as viewed in the direction of the arrow 2, as will be all subsequent description.

In making one revolution in a counterclockwise direction the gear 14 carries the frame 17 and dual element gears 23 and 24 with it, the elements 27 of which gears, in engagement with gears 29 and 30, will tend to carry both of these gears in the same counterclockwise direction, and it would seem that they are both free to do so with pawl 34 out of engagement with ratchet wheel 33 in the "Slow release" position of handle 44. However, at this time, the cable 10 is exerting a pulling force on the drum 9 which will tend to turn said drum and the gear 14 in a clockwise direction, exerting a force on gear elements 28 in such a manner as will cause the attached elements 27 to urge the gear 30 to turn clockwise. Since gear 30 is prevented from so turning, as the

frame 17 is turned one revolution counterclockwise carrying dual element gears 23 and 24 with it, the elements 27 of said gears will roll on the gear 30, making two revolutions on their own respective axes in so doing, and incidentally rotating the gear 29 which is now free to rotate in either direction. The attached elements 28 will also make the two revolutions about the same respective axes in a direction which will tend to allow the gear 45 to rotate one and one-half revolutions in a clockwise direction, the gear elements 28 having thirty teeth and the gear 45 forty teeth. At the same time, if elements 28 did not turn at all on their own axes, they would carry gear 45 one revolution in a counterclockwise direction with the frame 17, the net turns of the gear 45 and hence drum 9 will therefore be one and one-half turns in a clockwise direction less than one turn in the opposite direction, or one-half turn in a counterclockwise direction, for one turn of gear 14 in a counterclockwise direction during slow release of the brakes for the chosen example.

To effect quick release of the brakes, the operator will move the handle 44 to "Quick release" position, thereby effecting disengagement of the pawl 36 from the ratchet wheel 35, while the pawl 34 remains out of engagement with ratchet wheel 33, so that in this position of handle 44 both the gears 29 and 30 are free to turn in either direction.

The cable 18 may be still exerting a pull on drum 9 which will turn it in a clockwise direction pending full return of the brake shoes and rigging to a normal rest position, and gear 45 will turn with said drum, causing the gear elements 28 to turn freely about their respective axes, rotating the gears 29 and 30 in opposite directions, and allowing the frame 17 and gear 14 to remain stationary, so that the hand wheel 7 will not turn and need not be turned, as the tension in cable 18 is quickly released.

Summary

It will thus be seen that I have provided an improved winding mechanism which is particularly adapted for use in operating brake mechanism manually. By rotation of the operating handle in one direction, the slack in the brake mechanism may be taken up rapidly, while by subsequent rotation of the handle in the opposite direction the leverage ratio of the mechanism is increased for applying the brakes. The mechanism is self-locking, so that any brake application effected thereby will not unintentionally release. The rate of intentional release of the brakes may be controlled by the operator in turning the operating handle at a desired rate under one release condition of the mechanism, while a rapid release of the brakes may be effected under a second release condition of the mechanism without turning of the operating handle.

Having now described my invention, what I claim as new and desire to secure by Letters Patent, is:

1. Gear mechanism comprising in combination, a hand wheel, a first gear secured for rotation with said hand wheel, a second gear operably engaging said first gear and secured for rotation about a fixed axis, a rigid frame secured to said second gear for rotation therewith, two oppositely disposed pairs of coaxially arranged bevel gears carried by said frame for rotation about an axis projecting at right angles to said fixed axis, each of said pairs of bevel gears comprising a

5 first bevel gear element rigidly secured to a second bevel gear element of smaller diameter than said first bevel gear element, first and second bevel gears spaced apart and disposed within said frame in axial alignment with said fixed axis and in engagement respectively with said second bevel gear element of each of said pairs of bevel gears, pawl and ratchet means connected to said first and second bevel gears for locking one of said first and second bevel gears against rotation in one direction and the other of said first and second bevel gears against rotation in the opposite direction, means for unlocking said pawl and ratchet means, a third bevel gear disposed in alignment with said fixed axis and in engagement with said first bevel gear element of each of said pairs of bevel gears, and means to be operated secured for rotation with said third bevel gear.

2. Gear mechanism comprising in combination, a first gear adapted to be rotated about a fixed axis, a rigid frame secured to said first gear for rotation therewith, a pair of bevel gears carried by said frame and adapted to rotate about an axis projecting in a direction perpendicular to a projection of said fixed axis, said pair of bevel gears comprising a first bevel gear element and a second bevel gear element rigidly secured to and of smaller diameter than said first bevel gear element, first and second bevel gears of equal size spaced apart and disposed in alignment with said fixed axis in meshing engagement with said second bevel gear element, pawl and ratchet means connected to said first and second bevel gears for locking one of said first and second bevel gears against rotation in one direction and the other of said first and second bevel gears against rotation in the opposite direction, means for disengaging said pawl and ratchet means for unlocking said first and second bevel gears, a third bevel gear disposed in alignment with said fixed axis and in engagement with said first bevel gear element and means to be actuated secured for rotation with said third bevel gear.

3. Gear mechanism comprising in combination, a first gear adapted to be rotated about a fixed axis relative thereto, a frame secured for rotation with said first gear, a dual element bevel gear carried by said frame and rotatable about an axis projecting at right angles to said fixed axis, said dual element gear comprising a first bevel gear element and a second bevel gear element secured to and of larger diameter than said first bevel gear element in coaxial relationship therewith, two spaced apart bevel gears engaging said second bevel gear element, said two bevel gears arranged to rotate about said fixed axis, pawl and ratchet means for preventing one of said two spaced apart bevel gears from turning in one direction and the other of said two spaced apart bevel gears from turning in the opposite direction, another bevel gear engaging said first bevel gear element and arranged to rotate about said fixed axis, and means to be operated secured to rotate with said other bevel gear.

4. A winding mechanism comprising in combination, a casing, a rigid member adapted to be rotated about a fixed axis relative to said casing, a pair of gear elements carried by said rigid member and rotatable on an axis perpendicular to said fixed axis, said pair of gear elements comprising a first bevel gear element rigidly secured to a second bevel gear element of smaller diameter than said first bevel gear element, a first bevel gear disposed in coaxial alignment with said

fixed axis and in engagement with said second bevel gear element, a second bevel gear also disposed in alignment with said fixed axis spaced away from said first bevel gear and also in engagement with said second bevel gear element, a first ratchet wheel rigidly secured for rotation with said first bevel gear, a first pawl carried by said casing and disposed in normal engagement with said first ratchet wheel for preventing rotation thereof in one direction, a second ratchet wheel rigidly secured for rotation with said second bevel gear, a second pawl carried by said casing and disposed in normal engagement with said second ratchet wheel for preventing rotation thereof in a direction opposite to that which said first ratchet wheel is prevented from turning, a third bevel gear disposed in alignment with said fixed axis for engagement with said first bevel gear element, a drum secured for rotation with said third bevel gear, and a flexible element wound on said drum for operative connection to a device to be actuated.

5. In a winding mechanism, the combination with a casing, of a first gear disposed within said casing, and a second gear disposed within said casing and spaced away from said first gear, of a hollow shaft secured at its one end to said first gear for rotation therewith, said hollow shaft supported by said casing and extending outwardly therethrough, a second shaft secured at its one end to said second gear for rotation therewith, said second shaft being longer than said hollow shaft and extending therethrough, a first ratchet wheel secured to the opposite end of said hollow shaft for rotation therewith, a second ratchet wheel secured to the opposite end of said second shaft for rotation therewith, a first pawl pivotally connected to the casing for locking engagement with said first ratchet wheel to prevent its rotation in one direction, a second pawl pivotally connected to the casing for locking engagement with said second ratchet wheel to pre-

vent its rotation in a direction opposite to said one direction, spring means connected to said first and said second pawl for urging each into locking engagement with the respective ratchet wheels, and cam means manually operable to one position to effect disengagement of said first pawl from said first ratchet wheel and to another position to disengage said second pawl from said second ratchet wheel while maintaining said first pawl in disengagement from said first ratchet wheel.

15 6. Winding mechanism comprising a shaft to be actuated, a driven gear rigidly secured to said shaft, a rotatable driving member arranged coaxial to said gear, a gear element disposed with its axis at right angles to that of said driven gear and member and meshing with said driven gear, structure supporting said gear element for rotation with said driving member, a pair of gears of equal diameter arranged in coaxial relation to said driven gear and meshing with diametrically opposite portions of said gear element, ratchet means for holding one of said pair of gears against rotation in one direction, other ratchet means for holding the other of said pair of gears against rotation in the opposite direction, and means for releasing either one or both of said ratchet means.
